UNITED STATES PATENT OFFICE.

WILLIAM T. MORRIS, OF PARIS, ARKANSAS.

SNAP-HOOK.

SPECIFICATION forming part of Letters Patent No. 449,491, dated March 31, 1891.

Application filed July 22, 1890. Serial No. 359,500. (No model.)

To all whom it may concern:

Be it known that I, WILLIAM T. MORRIS, of Paris, in the county of Logan and State of Arkansas, have invented a new and useful Improvement in Snap-Hooks, of which the following is a full, clear, and exact description.

My invention relates to improvements in snap-hooks, the object being to produce a snap-hook which is especially adapted to be applied to back-bands for holding the traces of plow-harness.

The invention consists in the particular construction and arrangement of parts, as hereinafter fully described, and pointed out in the claims.

Reference is to be had to the accompanying drawings, forming a part of this specification, in which similar letters and numerals of reference indicate corresponding parts in all the figures.

Figure 1 is an edge view of a back-band having my improvement applied. Fig 2 is a side view of same, a trace being shown in dotted lines and in engagement with one of the snap-hooks; and Fig. 3 is a perspective view of the improvement.

Referring to the drawings, A is a back-band provided with straps C, by means of which the snap-hooks D, hereinafter described, are attached to the back-band, and B is a belly-band provided with rings or loops at its ends for engaging the snap-hooks.

The snap-hook D consists of a metal bar provided with a laterally-widened loop d, integrally formed at one end of said bar, the slightly-tapered body being bent at e, so as to return the free end portion 2 of the bar toward the flattened loop d, and at f a right-angle bend is given to the material to project a short limb g laterally, which limb at h is bent at a

right angle, so as to extend the terminal end portion i directly below the loop d and adjacent to it. Upon the side of the hook-bar, between the limbs 1 2 of the same, a flat plate-spring m is secured by its upper end near to 45 the loop d, the elastic body of the spring being projected downwardly and across the space between these limbs, causing the free end of the spring to impinge upon the inner face of the limb 2 a short distance from the 50 return-bend e.

In use, a snap-hook having been secured to each side of the back-band by the straps C, and the rings or loops of the belly-band having been engaged by the snap-hooks, the trace-chains are connected to the snap-hooks by 55 passing the hooks through a link of the chains.

Having fully described my invention, I claim as new and desire to secure by Letters Patent—

1. A safety snap-hook consisting of a loop, a hook depending from the loop and having its end bent laterally and then inwardly toward and under the loop, and a spring secured to the body of the hook and having its 65 free end projecting downward toward the outer member thereof, substantially as described.

2. A safety snap-hook consisting of the loop d, the downwardly-projecting body portion 1, 70 having the upwardly-bent limb 2, the laterally-projecting limb g, and the terminal end portion i, projecting under the loop d, and the spring m, secured to the body portion, substantially as herein shown and described.

WILLIAM T. MORRIS.
